[57] CLAIM

The ornamental design for an animated penguin figurine, substantially as shown and described.

DESCRIPTION

FIG. 1 is an isometric view showing the front, one side and portions of the animated penguin figurine showing my new design;

FIG. 2 is a side elevational view of the side not shown in FIG. 1;

FIG. 3 is a bottom plan view of the figurine of FIG. 1; and

FIG. 4 is a rear elevational view of the figurine of FIG. 1.
